(57) **CLAIM**

An ornamental design of a pet harness as shown and described.

DESCRIPTION

FIG. 1 is a top perspective view of an exemplary pet harness according to a new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a bottom perspective view thereof.

The equal-length broken lines on the pet harness depict stitching and form no part of the claimed design.

1 Claim, 8 Drawing Sheets
